CONTINUOUS MINING MACHINE AND
CONTROL SYSTEM THEREFOR

Sterling C. Moon, deceased, late of Dublin, Ohio, by
Katharyne M. Moon, administratrix, Dublin, Ohio,
assignor to Jeffrey Galion Manufacturing Company, a
corporation of Ohio
Original application Sept. 4, 1959, Ser. No. 838,110.
Divided and this application Nov. 6, 1962, Ser.
No. 235,888

12 Claims. (Cl. 299—1)

This patent application is a division of co-pending patent application, Serial No. 838,110, filed September 4, 1959, for an Improvement in a Continuous Mining Machine and Control System Therefor.

The instant invention relates to continuous mining machines for the mining of coal, which are adapted to be continuously advanced into the mine face to remove the coal therefrom, and which include conveying means to carry the mined material away from the mine face and to discharge the same at the rear of the machine, to permit the continuous advance of the mining machine into the face. More particularly the instant invention relates to a continuous mining machine in which there is provided a system for sensing the advance of the mining machine into the selected material in the mine face, which is the coal, with the sensing system providing signals indicating the advance of the mining machine into material other than the selected material, so that the course of advance of the mining machine may be guided in accordance with the signals to remove only the selected material from the mine face. The mining machine constructed in accordance with the instant invention further includes a control system for operating the mining machine from a position that is remotely located with respect to the mine face and the mining machine, the remote control system including the sensing system, and the mining machine being operated from the remote location in accordance with the signals which indicate the course of advance of the mining machine into the selected material.

It is a prime object of this invention to provide a continuous mining machine provided with a control system for the operation of the mining machine from a position that is spaced with respect to the mine face and the mining machine.

It is a further object of this invention to provide a continuous mining machine for removing selected material from a mine face, provided with a system for sensing the course of advance of the mining machine into the selected material and providing signals for indicating the course of advance of the mining machine with respect to the selected material in the mine face.

It is another object of this invention to provide a continuous mining machine for removing selected material from a mine face, in which the mining machine is advanced into a determinate area of the mine face, and is provided with sensing means for sensing the material at the limits of the determinate area of the mine face, and providing signals indicating the advance of the mining machine into material other than the selected material.

It is also an object of this invention to provide a continuous mining machine comprising a plurality of mining devices for removing material from a mine face, in which the mining devices are arranged transversely across the front of the mining machine to remove material from an area of the mine face coextensive with the sweep of the mining devices, with the outermost mining devices including sensing means for sensing the material of the mine face at outer boundaries of the area of the mine face from which selected material is removed, and including means to provide signals indicating the advance of the

2

mining devices into material other than said selected material.

It is still a further object of the instant invention to provide a continuous mining machine comprising mining devices adapted to be advanced into a mine face for removing selected material therefrom, with the mining devices being arranged one above the other to remove material from a selected area of the mine face coextensive with the sweep of the mining devices, the latter including sensing means for sensing the limits of the mine face area from which the selected material is removed, and including means to provide signals indicating the advance of the mining devices into material other than the selected material in the mine face.

A still further object of the instant invention is to provide a continuous mining machine comprising two transversely extending rows of mining devices, with said rows being adjustable upwardly and downwardly relatively to each other, and adapted to be advanced into a mine face for the removal of selected material therefrom, said mining devices defining a determinate area of the mine face from which the selected material is removed, and the outermost mining devices of each row defining the limits of said determinate area, and said outermost mining devices including sensing means to sense the material at the limits of the determinate area of the mine face, and including means providing signals indicating the advance of the mining devices into material other than said selected material.

It is also an object of the invention to provide a continuous mining machine comprising rotating mining devices adapted to be advanced into a mine face concurrently with the rotation thereof for removing material from the mine face, and said mining devices including means for indicating the rotary position of the mining devices.

Another object of the instant invention is to provide a continuous mining machine comprising rotating mining devices adapted to be advanced into a mine face for removing material therefrom, said mining devices being rotated in paths extending beyond the transverse perimeter of the mining machine to cut an area of the mine face of greater dimension than the transverse dimension of the mining machine, and being retractable within the perimeter of the mining machine, said mining devices including a signal system to indicate the position of the mining devices when they extend beyond the transverse perimeter of the mining machine.

Other objects of the invention will appear hereinafter, the novel features and combinations being set forth in the appended claims.

In the accompanying drawings:

FIGS. 1A and 1B together are a side elevational view of a continuous mining machine embodying the instant invention;

FIGS. 2A and 2B together are a plan view of the continuous mining machine of FIGS. 1A and 1B;

FIG. 3 is an elevational view of the continuous mining machine showing the mining heads and the hydraulic mechanisms for adjusting the same;

FIG. 4 is a front elevational view of the mining heads of the mining machine showing the disposition of the mining devices;

FIG. 5 is a sectional view of the lower mining head and a cutter arm showing elements of the sensing system;

FIG. 6 shows the cutter arm of FIG. 5 partially in section;

FIG. 7 is a front elevational view partially in section of the cutter arm of FIG. 6;

FIG. 8 is a partial sectional view of the cutter arm taken on the line 8—8 in FIG. 7;

FIG. 9 is an enlarged view of the rear portion of the mining head shown in FIG. 5;

FIG. 10 is a sectional view of the mining head showing elements of the sensing system and taken on the line 10—10 in FIG. 9;

FIG. 11 is a diagrammatic illustration of the hydraulic system for the mining machine of this invention;

FIGS. 12A to 12F together form a diagrammatic illustration of the electrical system for the continuous mining machine of this invention;

FIG. 13 is a plan view of the face of the control box embodying the electrical controls for the continuous mining machine of this invention; and

FIG. 14 is a side elevational view of the top of the control box shown in FIG. 12.

The instant invention relates to continuous mining machines, particularly such as are adapted to be used in the mining of coal in underground operations, or in other mining operations in which the mining machine is adapted to be advanced into the ground. Customarily the controls for such machines are placed at an operator's station at the side of the machine, and the operator of the machine accompanies it as it advances into the mine face, it being understood that it is a characteristic mode of operation of such a continuous mining machine that it forms a room or tunnel in the mine as it advances into the mine face, which room or tunnel is generally of greater dimension than the overall transverse dimensions of the machine, thereby providing room for the operator, and also providing room for backing the machine out of the room or tunnel and permitting it to be maneuvered into position to advance into another mine face.

It is recognized that there are certain dangers inherent in coal mining operations. It is accordingly customary to follow prescribed procedures for insuring the safety of those engaged in the coal mining operation. The inherent dangers connected with the mining of coal are further reduced by the provision of apparatus for removing the coal from the mine face without requiring the proximate presence of a machine operator at the machine. In accordance with the instant invention there is provided a continuous mining machine which is adapted for coal mining operations, and which includes a sensing system for sensing the material in the mine face and providing signals indicating the course of advance of the mining machine relative to the location of the coal in the mine face, so that the course of advance of the mining machine may be guided accordingly, to keep the mining machine in the coal seam. The continuous mining machine of this invention further includes a control system in which the sensing devices provide signals at a position remotely located with respect to the mining machine that indicate the advance of the mining machine, and controls at that remote position by which the mining machine may be operated.

Referring to the drawings, FIGS. 1-4, there is illustrated therein a continuous mining machine 30 embodying the instant invention, and comprising a main frame 31 supported on a pair of endless crawler traction treads 32, 33 disposed at opposite sides of the main frame 31. The continuous mining machine 30 is propelled in forward or reverse directions by the crawler traction treads 32, 33, and may be steered by operating the crawler traction treads 32, 33 at different speeds. The crawler traction treads 32, 33 are operated by individual hydraulic motors 34, 35, respectively, which are supported in the main frame 31. An identical mechanical drive extends between each of the hydraulic motors 34, 35 and the respective crawler traction treads 32, 33 for driving the latter. The drives to the crawler traction treads 32, 33 each comprises a pinion 36 driven by a hydraulic motor 34, 35 and driving a gear 37 which, in turn, drives a worm and worm wheel 38, the latter driving a pinion 39 which drives gear 40 that is co-axially mounted on a shaft with a drive sprocket 41 that is engaged with a crawler traction tread 32, 33 to drive the latter. The operation of each of the hydraulic motors

34, 35 may be reversed for driving the crawler traction treads 32, 33 in reverse, as when backing the continuous mining machine 30 away from a mine face. Also, the rate of delivery of hydraulic fluid to each of the motors 34, 35 may be independently varied to drive the crawler traction treads 32, 33 at different speeds for steering the continuous mining machine 30.

At the forward end of the continuous mining machine 30 there is a forwardly extending support 45 that is pivotally mounted on the main frame 31 on laterally extending pins 46. The support 45 extends forwardly from the main frame 31 along the floor 47 of the mine, with the support 45 being inclined downwardly in a forward direction, as best seen in FIG. 3.

The support 45 carries a lower mining head 48 and an upper mining head 49, which are disposed in substantial vertical alignment one above the other. The lower mining head 48 is pivotally connected to the support 45 by laterally extending pins 50. The upper mining head 49 is supported on the lower head 48 and includes depending guides 51 at the opposite sides thereof, which are engaged with tracks 52 on the lower mining head 48 for guiding the movement of the upper mining head 49 upwardly and downwardly relatively to the lower mining head 48.

A double acting hydraulic cylinder and piston mechanism 53 is connected between the main frame 31 and the support 45 and is operative to raise and lower the support 45 by swinging the same upwardly and downwardly on the pivot pins 46. A double acting cylinder and piston mechanism 56 is connected between the main frame 31 and the lower mining head 48, and by operation of the cylinder and piston mechanism 56 the lower mining head 48, as well as the upper mining head 49 which is supported on the lower mining head 48, are tilted forwardly and rearwardly on the axis of the pivot pins 50. A third cylinder and piston mechanism 57 is connected between the lower mining head 48 and the upper mining head 49, for raising and lowering the latter relatively to the lower mining head 48.

The lower mining head 48 comprises a gear box 58 that extends laterally across the forward end of the continuous mining machine 30. A plurality of transversely aligned shafts 59 extend forwardly from the gear box 58, there being five shafts 59 in the disclosed embodiment of the invention. A radially extending cutter arm 60 is secured to each shaft 59. Each cutter arm 60 comprises integral bit holders 61, each of which is adapted to receive a plurality of forwardly extending bits 62. Within the gear box 58 there is enclosed a train of gears for rotating all the shafts 59 simultaneously, and in timed relation to each other. As seen in FIG. 4, the cutter arms 60 have different circumferential positions. The two cutter arms 60 at the left side and the cutter arm 60 at the center of the mining head 48, as seen in FIG. 4, are rotated in a counterclockwise direction, while the two cutter arms 60 at the right side of the mining head 48 are rotated in a clockwise direction. The cutter arms 60 are each rotated at the same speed, and are disposed in different selected circumferential positions so that there is not interference of the cutter arms 60 with each other during the simultaneous rotation thereof.

The upper mining head 49 includes a gear box 63, which also encloses a gear train for rotating a plurality of transversely aligned shafts 64 that project forwardly from the front of the gear box 63. In the illustrated embodiment of the invention the upper mining head 49 is provided with ten shafts 64, each of which has secured thereto a radially extending cutter arm 65. Each cutter arm 65 includes integral bit holders 66 for the reception of forwardly extending mining bits 67. The five cutter arms 65 at the left side of the upper mining head 49, as viewed in FIG. 4, are rotated in a counterclockwise direction, and the five cutter arms 65 at the right side of the upper mining head 49 are rotated in a clockwise direc-

tion. All of the cutter arms 65 are rotated simultaneously at the same speed by the gears within the gear box 63, and are placed in different circumferential positions on the respective shafts 64, to avoid any interference between the cutter arms 65 during the simultaneous rotations thereof.

As illustrated in FIG. 4, the upper mining head 49 is separated or raised with respect to the lower mining head 48, for mining a maximum height of material from the mine face. The cutters arms 60, 65 on the respective mining heads 48, 49 each operate in circular paths which are overlapping. The cutter arms 60, 65 are advanced into the mine face by the operation of the crawler traction treads 32, 33 advancing the whole mining machine 30 forwardly. As the mining bits 62, 67 are brought into the mine face, these bits operate to cut and break the material out of the mine face. The circular paths of the cutter arms 60, 65 cumulatively define a mine face area from which material is removed in the mining operation. As seen in FIGS. 2 and 4, the laterally outermost cutter arms 60a, 60b, 65a, 65b at each side of the mining machine 30, extend laterally beyond the maximum lateral dimension of the mining machine 30, whereby there is produced as result of the mining operation a room or tunnel which is wider than the mining machine 30. Each of the cutter arms 60, 65 is an eccentric element extending to only one side of its shaft 59, 64, respectively, whereby upon rotation of the cutter arms 60, 65, the laterally outermost cutter arms 60a, 60b, 65a, 65b may be withdrawn from the sides of the tunnel or mine room, and disposed in positions lying within the transverse dimensions of the mining machine 30. The cutter arms 60a, 60b, 65a, 65b thus being moved to positions out of contact with the side walls of the mine room or tunnel, it is possible to freely maneuver the mining machine 30.

The forward end of the support 45 includes a transversely extending blade 70 which is adapted to be disposed on the floor 47 of the mine behind the lower cutter arms 60. Since the cutter arms 60 operate in circular paths, they form cusps of material in the mine floor 47, and the blade 70 operating behind the cutter arm 60 removes these cusps from the floor 47, leaving the latter relatively smooth and level for the advance of the crawler traction treads 32, 33 thereof.

The forward end of the main frame 31 supports a pair of electric motors 71, 72 for driving the lower mining head 48 and the upper mining head 49, respectively. The drive from the motors 71, 72 is delivered to a gear case 73 which combines the power of the motors 71, 72. A universal jointed drive shaft 74 extends from the gear case 73 to the lower mining head 48, and a second universal jointed drive shaft 75 extends from the gear case 73 to the upper mining head 49. The drive shafts 74, 75 each include telescoping sections to permit adjustment of the mining heads 48, 49, as previously described.

The support 45 also carries one end of an endless chain conveyor 78, which is guided around an idler sprocket assembly 79 at the forward end of the support 46. The conveyor 78 extends rearwardly from the forward end of the support 45, through the mine frame 31 of the mining machine 30, as best seen in FIG. 1, and terminates at the rear end of the mining machine 30, at which point the conveyor 78 discharges the mined material. The conveyor 78 comprises two individual chain conveyors arranged side by side and each including oppositely disposed endless drive chains 80, to the links of which there are secured a plurality of transversely extending flights 81, which are adapted to sweep the mined material over the bed 82 of the conveyor 78. The endless chain conveyor 78 is driven by a hydraulic motor 83 driving gears 84 which, in turn, drive a dual sprocket 85 that is connected by a chain drive 86 to dual sprockets 87, which are coaxially mounted on the driven shaft 88 with chain driving sprockets 89 that are engaged with the chains 80 for driving the latter.

The rotation of the cutter arms 65 of the upper mining head 49 is in such directions as to sweep the mined material towards the center of the mining machine 30. Similarly, the direction of rotation of the two outer cutter arms 60 at each side of the lower mining head 48 is in such directions as to sweep the mined material in towards the center of the mining machine 30. As the cutter arms 60, 65 are advanced into the mine face, the blade 70 works along the mine floor to remove the cusps left between the cutter arms 60, and also works its way into the material mined by the cutter arms 60, 65 to guide this material upwardly onto the support 45 to be received by the conveyor 78 and to be carried rearwardly thereby to the rear end of the mining machine 30 for discharge of the mined material therefrom. Since the mined material is carried away from the area of the mine face as it is mined, the advance of the cutter arm 60, 65 is not impeded and the mining operation may be carried on continuously. At each side of the lower mining head 48 there is provided a pivoted gathering guide 90, which also works to crowd the mined material in towards the center of the mining machine 30, to be received by the conveyor 78 for carrying this material away from the mine face.

It is a characteristic of coal that it is found in the ground in seams which lie in relatively level planes. The coal may vary in thickness within a given seam, and the same may rise and descend within the ground. Therefore it is customary for the operator of a continuous mining machine to view the face of the mine in which the mining machine is working to thereby visually determine whether the mining machine is following the coal seam. The mining heads 48, 49 are adjustable in a vertical direction relatively to each other for the purpose of adjusting to varying heights of coal in the coal seam. Thus where the coal seam is found to increase or decrease in height, the upper mining head 49 is elevated or lowered by means of the heads separating cylinder and piston mechanism 57, so that the vertical reach of the cutter arms 60, 65 is substantially equal to the height of the coal seam in which the machine is working. When the coal seam is found to drift upwardly or downwardly, the mining heads 48, 49 can be tilted either forwardly to operate the mining machine in a descending path, or the mining heads 48, 49 can be tilted backwardly to follow the coal seam in an ascending path, the tilting of the mining heads 48, 49 being accomplished by use of the tilting cylinder and piston mechanism 56. As a further adjustment in the following the ascending or descending path of the coal seam, the support 45 and the mining heads 48, 49 carried thereby, can be raised by means of the raised cylinder and piston mechanism 55.

Above and below the coal seam there is generally found material which is relatively harder than the coal, such as rock or shale. Ideally, it is desired that the cutter arms 60, 65 not enter the relatively harder material which is found above and below the coal seam, for the reason that this material is waste as far as the coal mining operation is concerned, and any such material removed from the mine face with the coal must later be separated from the coal product. Also the operation of the cutter arms 60, 65 in material that is relatively harder than coal produces excessive wear on the mining bits 62, 67, thereby severely reducing the life thereof, and making necessary more frequent replacement of the bits, which of course interrupts the mining operation and is therefore undesirable.

With the continuous mining machine 30 embodying the instant invention it is intended to make unnecessary visual observation of the mine face, and for this purpose the cutter arms 60, 65 include sensing means for the purpose of sensing the course of advance of the mining machine, and more particularly the advance of the mining bits 62, 67 of the cutter arms 60, 65, respectively, into material that is relatively harder than the coal. The sensing

ing means is included in a signaling system so constructed that it provides signals at a location remote from the mine face indicating the advance of the mining machine into material that is relatively harder than the coal. These signals are provided continuously during the operation of the cutter arms 60, 65 at a remotely located station at which all the controls for the mining machine 30 are located, as will be described in greater detail hereinafter, thereby making it unnecessary for the machine operator to take a position immediately adjacent the mining machine when the signals provided by the signaling system indicate that the mining machine is advancing into material relatively harder than coal, the mining heads 48, 49 are adjusted as previously described to move the mining bits 62, 67 back into the coal seam, such adjustment being made in accordance with the signals of the signaling system. Similarly, the limits of the coal seam may be located by adjustment of the mining heads 48, 49. During such exploratory adjustment the signaling system will indicate the entry of the mining bits 62, 67 into material other than coal, whereupon the mining heads 48, 49 may be adjusted back to just clear the material other than coal, and the mining operation will proceed with only the removal of coal from the mine face.

As seen in FIG. 4, the cutter arms 60, 65 remove material from a determinate area 91 of the mine face, which is defined by the cumulative rotary sweep of the several cutter arms 60, 65 in the lower and upper rows of cutter arms respectively. The limits of the determinate area 91 of the mine face from which the material is removed are defined by the two outermost lower cutter arms 60a, 60b of the lower mining head 48, and by the two outermost cutter arms 65a, 65b of the upper mining head 49. Considering that the coal is found in laterally extending seams which are of a fairly regular nature, it is sufficient in sensing the location of the coal seam to perform this sensing function at the limits of the determinate mine face area 91 from which coal is removed by the cutter arm 60, 65. Accordingly, the sensing devices are incorporated in each of the cutter arms, 60a, 60b, 65a, 65b. Since it is merely necessary to sense the material of the mine face at the limits of the determinate area 91 of the mine face from which the coal is removed, the sensing devices in the cutter arms 60a, 60b, 65a, 65b each operates in a quadrant which is co-extensive with a corner of the determinate mine face area 91 defined by the cumulative sweep of all the cutter arms 60, 65.

In the operation of the continuous mining machine 30 embodying the sensing devices in the several cutter arms, if the cutter arm 65a senses material other than coal in the mine roof, the upper cutter head 49 can be lowered relatively to the lower cutting head 48 to thereby get below the relatively harder material, so that the mining machine in its continued operation will be operating solely in coal. Upon continued operation of the mining machine it may be found that the disposition of the relatively harder material in the roof of the mine indicates that the coal seam is drifting downwardly, which will call for a forward tilting of the mining heads 48, 49 to operate the mining machine in a descending path. Depending on the location of the coal seam as determined by the several sensing devices, it may be found that a further adjustment is needed to lower the support 45 and the blade 70 to follow the downward drift of the coal seam for the purpose of removing the maximum height of coal from the mine face.

During operation of the mining machine 30, where the sensing devices in either the cutter arms 60a, 60b or the cutter arms 65a, 65b do not provide any signals indicating the presence of material harder than the coal below or above the coal seam, the mining heads 48, 49 and the blade 70 may be adjusted upwardly and downwardly until there are produced signals indicating the location of the relatively harder material, following which the mining

heads 48, 49 and the blade 70 may be further adjusted to clear the relatively harder material, and to remove the maximum height of coal from the mine face. Since the signaling system continuously provides signals to the operator at the control station for the mining machine, it is a relatively simple matter for him to make adjustments of the mining mechanisms of the machine as described hereinabove, directed to the purpose of removing the maximum amount of coal from the mine face.

Referring to FIGS. 5 to 10, there is illustrated therein the cutter arm 60a embodying the sensing device for sensing the material of the mine face, and for producing a signal at a remote station indicating the advance of the cutter arm 60a into material that is relatively harder than the coal. The cutter arm 60b is identical to the cutter arm 60a. The upper cutter arms 65a, 65b are shorter than the cutter arms 60a, 60b and only include a single bit holder. However, the sensing device embodied in each of the cutter arms 65a, 65b is similar in all respects to the sensing device embodied in each of the cutter arms 60a, 60b.

The cutter arm 60a, as best seen in FIGS. 5 and 7, includes an integral bit holder 61 located approximately midway along the length of the arm 60a, and a separable bit holder 92 at the outer end of the cutter arm 60a. The bit holder 92 is formed with a laterally extending shaft 93 which is received in a radially extending socket 94 in the cutter arm 60a. The shaft 93 is supported in the socket 94 by sleeve bearings 95, to permit oscillation of the shaft 93 and the bit holder 92 relatively to the cutter arm 60a. The bit holder 92 is disposed within the bifurcated end 96 of the cutter arm 60a, and works in the mine face in a counterclockwise direction, as viewed in FIG. 7. At one side of the bifurcated end 96 of the cutter arm 60a there is seated a resilient backing member or stop 97 abutting the rear side of the bit holder 92. The backing member 97 is preferably made of relatively hard rubber, although other resilient devices may be utilized. The stiffness of the backing member 97 is so gauged that it will resist and prevent movement of the bit holder 92 on the axis of the shaft 93 relatively to the cutter arm 60a, when the mining bits 62 are operating in coal. However, when the mining bits 62 are worked into material that is relatively harder than the coal, they meet with increased resistance applying a greater than normal force to the bit holder 92, overcoming the resistance of the backing member 97 and causing movement of the bit holder 92 relatively to the cutter arm 60a, and resulting in oscillation of the shaft 93.

The end of the shaft 93 extends into a chamber 98 formed in the cutter arm 60a. A lever arm 99 is keyed to the end of the shaft 93 and secured thereto by a nut 100. The lever arm 99 extends radially from the shaft 93 into engagement with the actuator 101 of a switch 102 secured to a wall of the chamber 98, and which, in the embodiment of the invention described herein, is a micro-switch. When the mining bits 62 of the bit holder 92 are worked into material that is relatively harder than coal, there results a movement of the bit holder 92 relatively to the cutter arm 60a, and a rotation of the shaft 93 and the lever arm 99, thereby operating the actuator 101 and closing the switch 102. The switch 102 is connected in an electrical circuit, which is operated thereby, to provide a signal at the operator's remotely located station to indicate the advance of the mining machine 30 and the mining bits 62 into material that is relatively harder than the coal.

The cutter arm 60a is mounted on the forwardly projecting end of the shaft 59a. The shaft 59a extends through the gear box 58 of the lower mining head 48. The rear end of the shaft 59a is rotatably supported by a tapered roller bearing 105, and the shaft 59a is rotatably supported at the front of the gear box 58 by another tapered roller bearing 106. Between the bearings

105, 106 a gear 107 is secured to the shaft 59a, and forms a part of the gear train enclosed in the gear box 58 for simultaneously rotating the shaft 59a and the other shafts 59 of the lower mining head 48. The cutter arm 60a includes a substantially radially extending bore 108 for the reception of an electrical cable 109 which is connected to the switch 102. The shaft 59a includes an axially extending bore 110, that extends through substantially the full length of the shaft 59a, and connects to the bore 108, for leading the electrical cable 109 from the switch 102 through the cutter arm 60a and through the shaft 59a to the rear end of the latter. The electrical cable 109 is secured in the end of the bore 108 by a packing nut 111 that prevents movement of the cable 109 in the bore 108 relatively thereto. The cable 109 includes two electrical conductors 116, 117 having their ends 103, 104, respectively, electrically connected to the switch 102 in the chamber 98. A cover 113 closes the chamber 103, and is bolted to the cutter arm 60a, and may be removed therefrom to provide access to the chamber 98. The electrical cable 109 emerges from the bore 110 through a packing nut 114, that clamps the end of the cable 109 in the end of the bore 110 and prevents movement of the cable 109 relatively thereto.

An insulating mounting block 115 is fitted into the end of the shaft 59a. The two electrical conductors 116, 117 of the electrical cable 109 each extends through separate bores in the mounting block 115. The conductor 117 is connected to a terminal 118 of a centrally disposed electrical contact spring 119. The conductor 116 is connected to a terminal 120, which is secured to the mounting block 115. A pigtail 121 is connected to the terminal 120 and to a brush 122, which extends rearwardly in an axial direction from a brush holder 123 secured to the mounting block 115. The brush holder 123 includes a compression spring 124 which urges the brush 122 rearwardly into contact with a solid ring conductor 125. The ring conductor 125 is mounted on an insulating mounting block 126, secured by a machine screw 127 to a mounting cover 128, which is bolted to the rear of the gear box 58. Within the ring conductor 125 there is received an insulating mounting block 129, on which there is supported an electrical contact 130, with machine screws 131 securing the contact 130 and the mounting block 129, to the mounting block 126, with the ring conductor 125 being held between the mounting blocks 126, 129. The contact spring 119 engages the electrical contact 130, and the brush 122 contacts the ring conductor 125.

The mounting cover 128 includes several rearwardly extending bores 132, through each of which an electrical cable 133 enters the chamber 134 formed in the rear of the gear box 58 for the various electrical devices. The electrical cable 133 is secured in the bore 132 by a packing nut 135 that prevents relative movement of the cable 133, which might cause abrasion thereof and damage. An electrical conductor 140 extends from the electrical cable 133 through bores in the mounting blocks 126, 129, and is electrically connected to the electrical contact 130. A second electrical conductor 141 extends through a bore in the mounting block 126 and is electrically connected to the ring conductor 125.

An electrical conductor 142 is connected to the terminal 120 and extends through the mounting block 115 and insulating plate 143, which is secured to the end of shaft 59a by a plurality of bolts 144. A brush holder 145 is secured to the rear of the insulating plate 143 by a pair of screws 146, and the electrical conductor 142 is connected to the terminal 147 on the brush holder 145. A pigtail 148 is also connected to the terminal 147 and connects to the brush 149 in the brush holder 145. A coiled leaf spring 150 has its coiled end secured to the brush holder 145, and its leaf end engaged with the top of the brush 149, to urge the latter into contacting engagement with a commutator 151, formed with a plurality of individual segments 152 around the periphery thereof. Those commutator segments 152

extending through a quadrant corresponding to the quadrant of the sweep of the cutter arm 60a defining a limit of the determinate area 91 of the mine face from which material is removed by the cutter arm 60a, each has connected thereto an individual electrical conductor 153. Within the mounting cover 128 there is secured an insulating keeper plate 154 that surrounds the commutator 151.

By the various electrical devices described hereinabove there are established several electrical circuits. In these electrical circuits the brushes 122, 149, and the contact spring 119 are secured to the shaft 59a and rotate therewith, while the remaining elements in the electrical circuits are fixed within the chamber 134, being secured to the mounting cover 128 which closes the chamber 134. By removal of the mounting cover 128, the electrical contact 130, the ring contact 125, and the commutator 151 are removed from the chamber 134, providing access to the other elements contained therein and secured to the rear end of the shaft 59a.

20 The continuous mining machine 30 described herein is adapted to be operated by direct current, and the electrical conductors 140, 141 are each connected to the positive side of the circuit. The conductor 140 connects through the contact 130 and the contact spring 119 to the electrical conductor 117 which leads to the switch 102 in the cutter arm 60a. The circuit on the other side of the switch 102 is formed by the electrical conductor 116 connecting to the terminal 120, and through the conductor 142 and the pigtail 148 to the brush 149. The commutator segments 152 are contacted by the brush 149, and the circuit on the negative side of the switch 102 is completed by the electrical conductor 153 connected to the commutator segments 152. Closing of the switch 102 by the action of the lever arm 99 energizes this circuit to provide a signal at the operator's station, which will be described in greater detail hereinafter.

25 The electrical conductor 141 is also connected to the positive side of the circuit and forms an alternate circuit with respect to the circuit above described. The electrical conductor 141 connects to the ring conductor 125 which is in contacting engagement with the brush 122. The pigtail 121 connects from the brush 122 to the terminal 120 and through the conductor 142 to the pigtail 148 of the brush 149. The brush 149 is in contacting engagement 30 with the commutator segments 152 which are connected in the circuit by electrical conductors 153. This circuit includes a remotely located switch, which will be described hereinafter, by which this alternate circuit can be energized to provide a signal to the remotely located operator's station in the same manner as the first circuit. Since this alternate circuit does not include the switch 102 in the cutter arm 60a, this circuit is not dependent upon the operation of the cutter arm 60a for providing a signal to the operator of the machine. The signal provided to the machine operator by the alternate circuit will show the rotary position of the cutter arm 60a within its operating quadrant that defines a limit of the determinate mine face area 91 from which material is removed by the mining machine. The operation and function of the various electrical elements hereinabove described, and the electrical circuits in which they are included will be described in greater detail hereinafter in connection with the electrical circuit diagram, FIG. 21.

35 The continuous mining machine 30 is operated and controlled by various hydraulic mechanisms diagrammatically illustrated in FIG. 11, which shows the hydraulic circuits for the machine. The hydraulic system includes a hydraulic head pump 160 which supplies the hydraulic fluid under pressure for operating the cylinder 70 and piston mechanism 55 for raising the mining heads 43, 49, the cylinder and piston mechanism 56 for tilting the mining heads 48, 49, and the cylinder and piston mechanism 57 for separating the mining heads 48, 49 by elevation of the mining head 49 relatively to the mining head 48. The hydraulic pump 160 also supplies

hydraulic fluid under pressure for operating various controls in the hydraulic system illustrated in FIG. 11, as will be described in greater detail hereinafter. Another hydraulic pump 161 supplies hydraulic fluid under pressure for operating the hydraulic traction motors 34, 35 which drive the crawler traction treads 32, 33, respectively. A third hydraulic pump 162 supplies hydraulic fluid under pressure for driving the hydraulic motor 83 which operates the conveyor 78. By the use of certain controls in the hydraulic system the hydraulic fluid supplied under pressure by the hydraulic pump 162 can be combined with the hydraulic fluid supplied to the hydraulic traction motors 34, 35 for driving the latter at high speed when the mining machine is being trammed other than in a mining operation. When the hydraulic pump 162 is so used it does not supply any hydraulic fluid to the hydraulic conveyor motor 83. As seen in FIG. 2B, each of the hydraulic pumps 160, 161, 162 is mechanically connected to a gear housing 163, which encloses a train of gears for transmitting driving power to the several hydraulic pumps from an electrical motor 164, which drives the gear train in the gear housing 163 and supplies power thereto.

The hydraulic pump 160 supplies hydraulic fluid under pressure through a pressure relief valve 165 to a bank of three solenoid controlled, pilot operated control valves 166, 167, 168. The control valve 166 is connected to the cylinder and piston mechanism 55 for raising the mining heads 48, 49, the control valve 167 is connected to the cylinder and piston mechanism 56 for tilting the mining heads 48, 49, and the control valve 168 is connected to the cylinder and piston mechanism 57 for separating the mining heads 48, 49.

Each of the cylinder and piston mechanisms 55 is double acting, and when hydraulic fluid is delivered to the cylinder and piston mechanism 55 through the hydraulic line 196, hydraulic fluid is exhausted from the opposite ends of the cylinder and piston mechanisms 55 through the hydraulic line 198.

When hydraulic fluid under pressure is delivered through hydraulic line 198 to one end of the cylinder and piston mechanisms 55, hydraulic fluid exhausts from the other end of the cylinder and piston mechanisms 55 through hydraulic line 196.

The hydraulic line 196 includes a check valve 199 which permits the free flow of hydraulic through the line 196 to the cylinder and piston mechanisms 55, but normally prevents return flow of hydraulic fluid through the line 196, so that the cylinder and piston mechanisms 55 will maintain their adjusted positions. The line 198 is open so that hydraulic fluid can be freely exhausted from the cylinder and piston mechanisms 55 through this line. When hydraulic fluid is delivered under pressure to the cylinder and piston mechanisms 55 through the line 198, this hydraulic fluid under pressure is also communicated through the pilot line 200 to a pilot 201 which operates to open the check valve 199, to permit the exhaust of hydraulic fluid from the cylinder and piston mechanisms 55 through the hydraulic line 196. The pilot 201 includes a return spring 201' for restoring pilot 201 and closing check valve 199.

The solenoid controlled, pilot operated control valves 166, 167, 168 are connected in series, the tank port of the valve 166 being connected to the pressure port of the valve 167, and the latter is similarly connected to the valve 168. Any one of the solenoid controlled, pilot operated control valves 166, 167, 168 may be individually operated to adjust the cylinder and piston mechanisms 55, 56, 57, respectively. The hydraulic circuit connecting the control valves 167, 168 to the cylinder and piston mechanisms 56, 57, respectively, is the same as that connecting the control valve 166 to the cylinder and piston mechanisms 55, and operate in the same manner.

The tank port of the solenoid controlled, pilot operated control valve 168 is connected to a hydraulic line 202 which delivers hydraulic fluid under pressure to a solenoid controlled pilot valve 203. The pressure of the hydraulic fluid in the hydraulic line 202 is less than the pressure of the hydraulic fluid delivered to the control valves 166, 167, 168, and is maintained at the lower value by the pressure relief valve 204.

The solenoid controlled pilot valve 203 controls and operates a double acting pilot 220 by the selective delivery of hydraulic fluid to the latter.

A manifold hydraulic line 221 delivers hydraulic fluid under pressure to solenoid controlled pilot valve 222 which is identical to the solenoid controlled pilot valve 203. A manifold tank line 219 connects pilot valves 203, 222 to the tank. The pilot valve 222 operates a double acting pilot 223 in the same manner as the pilot valve 203 operates the pilot 220. The pilot 220 is connected to a reversing valve 224 and the pilot 223 is connected to a similar reversing valve 225. The reversing valves 224, 225 are oppositely disposed, but are otherwise identical and control the direction of operation of the hydraulic traction motors 34, 35, respectively.

The manifold hydraulic line 221 also delivers hydraulic fluid under pressure to the solenoid controlled pilot valve 226.

The solenoid controlled pilot valve 226 operates a pair of double acting pilots 240, 241 which have common connections to the pilot valve 226. The pilot 240 is mechanically connected to a flow control valve 245, and the pilot 241 is similarly mechanically connected to a flow control valve 246. The flow control valves 245, 246 are operative to deliver hydraulic fluid under pressure to the conveyor hydraulic motor 83 through a common hydraulic line 247, or alternatively, the flow control valves 245, 246 operate to deliver the hydraulic fluid under pressure to the reversing valves 224, 225, respectively, for combining the hydraulic fluid which is normally delivered to the hydraulic conveyor motor 83 with the hydraulic fluid delivered to the traction motors 34, 35 for operating the latter at a high speed, as when the mining machine 30 is trammed during times other than when it is in mining operation.

The hydraulic manifold line 221 also delivers hydraulic fluid under pressure to each of a pair of solenoid controlled pilot valves 250, 251, which are identical to the solenoid controlled pilot valve 226. The pilot valve 250 supplies hydraulic fluid under pressure to a double acting pilot 252, and the pilot valve 251 supplies hydraulic fluid under pressure to a double acting pilot 253. The pilot 252 operates a volume control valve 278, and the pilot 253 operates a volume control valve 277, which govern the volume of hydraulic fluid delivered to the reversing valves 225, 224, respectively.

The hydraulic manifold line 221 also delivers hydraulic fluid under pressure to a solenoid controlled pilot valve 254 which is identical to the solenoid controlled pilot valve 203. The pilot valve 254 delivers hydraulic fluid under pressure to a conveyor reversing valve 255 which is operated by the hydraulic fluid.

The hydraulic pump 161 delivers hydraulic fluid under pressure for operating the hydraulic traction motors 34, 35 that drive the traction treads 32, 33, respectively, in advancing the mining machine during the mining operation. The hydraulic line 275 connects the hydraulic pump 161 through a pressure relief valve 274 to a flow divider valve 276 which divides the flow of hydraulic fluid evenly, and supplies the divided hydraulic fluid to the volume control valves 277, 278 through hydraulic lines 279, 280, respectively. The volume control valves 277, 278 are operative to control the volume of hydraulic fluid delivered to the hydraulic traction motors 34, 35, respectively, thereby controlling the speed of the hydraulic motors 34, 35.

The volume control valve 278 is similar to the volume

control valve 277, and is similarly connected in the hydraulic circuit to operate in the same manner with respect to the delivery of hydraulic fluid for operation of the hydraulic traction motor 35. In the normal operation of the mining machine 30 it is desired to advance forwardly in a straight line which calls for operating the crawler traction treads 32, 33 at equal speeds. For this purpose the volume control valves 277, 278 are set to deliver the same volume of hydraulic fluid to each of the hydraulic traction motors 34, 35. However, should it be desired to steer the mining machine 30 during the mining operation, or at any other time, such steering is accomplished by varying the volume of hydraulic fluid delivered to the respective hydraulic traction motors 34, 35, this being accomplished by corresponding operation of the pilots 252, 253 for the volume control valves 278, 277, respectively.

The hydraulic fluid from the volume control valve 277 is delivered through hydraulic line 290 to the reversing valve 224, and the hydraulic fluid is delivered from the volume control valve 278 through the hydraulic line 292 to the reversing valve 225. The reversing valves 224, 225 are integral parts of a four unit valve 295. The reversing valves 224, 225 are similar, except that they are oppositely disposed in the four unit valve 295. The four unit valve 295 also includes the pilots 220, 223 for operation of the reversing valves 224, 225, respectively.

Combined with the hydraulic system for operating the mining machine 30, there is provided an electrical system which includes controls for the mining machine, electrical controls for the various hydraulic control devices, and the signaling system by which signals are provided indicating the advance of the mining machine with respect to the coal seam. The electrical system is diagrammatically illustrated in FIGS. 12A to 12F. In the electrical circuit diagram, that part of the circuit which is included within the dot-dash line 355 represents electrical equipment on the mining machine 30. That portion of the electrical circuit diagram included within the dot-dash line 356 represents electrical equipment which is included within a control box 357, seen in FIG. 1B. That portion of the electrical circuit diagram between the dot-dash lines 355, 356 represents an electrical cable 358 which extends between the control box 357 and a junction box 359 at the rear end of the mining machine 30.

In accordance with this invention the electrical controls for operating the mining machine 30 are included in the control box 357, which is supported on a wheeled truck 366 to permit the same to be readily moved to follow the mining machine 30. The electrical cable 358 is connected at one end to the control box 357, and at its other end to the junction box 359 on the mining machine 30, whereby the current is conducted between the control box 357 and the mining machine 30 for operating the various electrical devices on the mining machine 30. The electrical cable 358 may be made in one continuous length, or it may be made of several shorter lengths to facilitate storage of the cable 358. Where the electrical cable 358 comprises several shorter lengths, the several lengths of cable are connected to each other between the mining machine 30 and the control box 357 by a connector box 360 having a plug portion 361 and a socket portion 362, by which the separate lengths of cable 358 are electrically connected to each other. The connector box 360 is mounted on a skid base 363 to facilitate moving the same along the mine floor. A plurality of cable clamps 364 are secured to the cable 358 at equally spaced positions along the length thereof, and lengths of chain 365 are secured to the cable clamps 364, and between the latter and the mining machine 30, the connector box 360, and the wheeled truck 366. By means of the chain 365 the cable 358 and the connector box 360 may be readily pulled along the mine floor without the transmission of any force to the cable 358, thereby avoiding any damage to the latter.

The mining machine 30 includes a positive terminal 370

and a negative terminal 371 for connecting a trailing power cable 367 to the mining machine 30, which supplies direct current power to the machine from a remotely located power source. The positive and negative lines 372, 373 include switches 374, 375, and a resistance 382 to limit the current in lines 372, 373. The switch 374 is located in the connector box 360 and is adapted to be opened prior to separation of the plug portion 361 from the socket 362 of the connector box 360. The control box 357 similarly includes a plug portion 376 and a socket portion 377, which are adapted to be joined for connecting the conductor cable 358 to the various electrical devices in the control box 357. The switch 375 is located in the control box 357, as seen in FIG. 13, and is adapted to be opened prior to separation of the plug portion 376 from the socket portion 377 in the control box 357. The plug portion 376 is secured to the socket portion 377 by a plurality of bolts 368. There is also included a bolt 369 which is so placed that it will close the switch 375 when it is threaded into the plug portion 376 and the socket portion 377 of the control box 357. When connecting the plug portion 376 to the socket portion 377 all the bolts 368 are first secured, and the bolt 369 is secured last, whereby it is insured that all the electrical connections are firmly made before there is energization of any of the circuits. When the plug portion 376 is separated from the socket portion 377, the bolt 369 is first removed to open the switch 375, and then the bolts 368 are removed. The plug portion 361 and the socket portion 362 of the connector box 360 are similarly constructed and include the switch 374 which is similar to the switch 375, and is opened prior to separation of the plug portion 361 from the socket portion 362. Opening of either of the switches 374, 375 de-energizes the electrical circuits in the mining machine 30 as well as those extending to the control box 357, and operates as a safety feature for this equipment. When the cable 358 is connected through the connector box 360, or is connected to the control box 357, the switches 374, 375 respectively are closed after all of the other electrical connections are made, thereby avoiding the possibility of any incendiary spark.

The terminal circuit includes a relay 378 having a coil 379, which is placed in the negative line 372. The relay further includes dual contactors 380 which are adapted to close the several circuits connected to the positive line 373. When the power line 367 is connected to the terminals 370, 371, and the switches 374, 375 are closed, the coil 379 is energized to operate the contactors 380 to close their circuits. When either of the switches 374, 375 is opened, or the power is disconnected from the terminals 370, 371, the relay coil 379 is de-energized, which induces a reverse voltage in the coil 379, which normally produces an incendiary spark at the point where the circuit is opened. In order to avoid the production of this incendiary spark, which is a dangerous condition in a mine, a rectifier 381 is connected across the coil 379, thereby rendering the circuits safe. Of course, when the circuit including the coil 379 is opened, the latter is de-energized, opening the dual contactor 380 and thereby de-energizing the other circuits as well. Should the positive lead of the power cable 367 be mistakenly connected to the negative terminal 371, the rectifier 381 shunts the current around the coil 379, and the latter will not be energized, and none of the electrical circuits can be operated until such time as the power cable 367 is properly connected to the terminals 370, 371 in accordance with the polarity thereof.

The commutator 151, as previously described, is concentrically disposed with respect to the axis of the shaft 59a, and corresponds in position to the circular path of the lower right cutter arm 60a. The segments 152 of the commutator 151 which lie in the quadrant corresponding to the quadrant of operation of the cutter arm 60a defining the lower right limit of the determinate area 91

of the mine face from which coal is removed by the mining machine, are connected by lines 385 to a bank of lights 386, which are disposed in a quadrant corresponding to the quadrant in which the commutator segments 152 are disposed.

The lower left cutter arm 60b includes a sensing device and signaling system identical to that of the cutter arm 60a, having a commutator 387. The commutator segments 388 corresponding to the quadrant of operation of the cutter arm 60b defining the lower left limit of the determinate mine face area 91 from which coal is removed, are connected by lines 389 to a bank of lights 390, disposed in a quadrant corresponding to the quadrant of commutator segments 387. The upper cutter arms 65a, 65b each includes a sensing device and signaling system like that of the cutter arm 60a, with the signaling systems being set to sense the material of the mine face in quadrants at the upper outer limits of the determinate mine face area 91 from which the coal is removed. The right upper cutter arm 65a has a signaling system including the commutator 391 having a quadrant of commutator segments 392 connected by lines 393 to a bank of lights 394 corresponding in position to the commutator segments 392. The signaling system of the upper left cutter arm 65b includes a commutator 395 having a quadrant of commutator segments 396, connected by lines 397 to a bank of lights 398 corresponding in position to the commutator segments 396. The lights 386, 394 are disposed in staggered positions in the arc of a half circle, with the lower half of the lights 386, including the odd light, being connected to the commutator 151, and the upper half of the lights being connected to the commutator segments 392. The lights 390, 398 are similarly but oppositely disposed in the arc of a half circle, and are connected to the commutator segments 388, 396, respectively.

The brush 149 in the signaling system for the lower right cutter arm 60a is mechanically connected to the shaft 59a, and is rotated thereby around the stationary commutator 151. The switch 102 is disposed in the cutter arm 60a and is adapted to be closed by the yielding action of the bit holder 92 when it encounters material in the mine face that is relatively harder than coal. The circuit is energized through the contact spring 119 and the contact 130, through the switch 102 to the brush 149, and through that commutator segment 152 with which the brush 149 is in contact. By energization of the circuit current is thereby supplied to a light 386, which corresponds in position to the position of the cutter arm 60a at which it encountered the relatively harder material in the mine face, which caused the closing of the switch 102. It is thus seen that the lights 386 are energized when the cutter arm 60a encounters relatively harder material than coal in the mine face, and provides a signal showing the presence of such material, and also showing the position of the cutter arm 60a at which it encountered the relatively harder material. As previously described the operation of the signaling system is in the quadrant of operation of the cutter arm 60a defining the lower right limit of the determinate mine face area 91 from which coal is removed.

An alternate circuit is provided for shorting out the switch 102. This circuit includes the switch 399, which closes the circuit through the brush 122 and the ring contact 125, and thence through the brush 149 and that commutator segment 152 with which the brush 149 is in contact, to illuminate one of the lights 386. This operation, of course, is not dependent on the sensing of material that is relatively harder than coal, since the switch 102 is bypassed. This circuit may be used to test the operation of the signaling system, or it may be used to check the position of the cutter arm 60a after it has stopped rotating. A like alternate circuit is provided for each of the other cutter arms 60b, 65a, 65b. The cutter arms 60a, 60b, 65a, 65b, during the cutting operation, operate in paths

that extend beyond the lateral dimension of the mining machine 30. The cutter arms 60a, 60b, 65a, 65b may be rotated to positions in which they are all located within the lateral dimensions of the mining machine 30, which will take them out of contact with the side walls of the tunnel or room being bored by the mining machine 30, and will facilitate maneuvering of the mining machine 30 since the cutter arms will not abut the mine walls. In moving the cutter arms 60a, 60b, 65a, 65b to their retracted positions, the movement thereof can be checked by use of the alternate circuit by closing switches 399, 400. Switch 399 will operate the signaling system with respect to cutter arms 60a, 65a, and switch 400 will operate the signaling system with respect to cutter arms 60b, 65b. The movement of the several cutter arms will be indicated by the successive illumination of the lights 386, 390, 394, 398, and when none of the lights is illuminated by rotation of the several cutter arms, it is known that the cutter arms 60a, 60b, 65a, 65b are all disposed within the lateral dimension of the mining machine 30, and out of contact with the mine walls.

Only the signaling circuit for the lower right cutter arm 60a has been described in detail for the reason that the signaling circuit for each of the other cutter arms 60b, 65a, 65b is identical to that described with respect to cutter arm 60a, as seen in FIG. 12. The lights 386, 394, 390, 398 are oppositely disposed on the face of the control box 357, as seen in FIG. 13. At the top of the face of the control box 357 there are provided dual switch actuators 418, 419 for the switches 399, 400, respectively, by which the alternate light circuits are closed. Each switch actuator 418, 419 has an "on" position for operating the alternate light circuits, and an automatic position in which the light circuits are operated through the switches 102 in the cutter arms for sensing the mine face. The light circuits further include a resistance 401 connected in series with each one of the lights 386, 390, 394, 398 for reducing the voltage to the lights commensurate with the size thereof. In the circuits described thus far there is further provided dial lights 402, 403, which are located on the face of the control box 357 to illuminate the same. Each light 402, 403 has a resistance 404 to limit the voltage supplied to the respective lights 402, 403. The signaling circuits including the switches 102 are supplied with current from the line 405, which is a positive line, and the alternate light circuits are supplied with current from a positive line 406. The current in the lines 405, 406 is limited by a resistance 407 connected in series with each of the lines 405, 406.

A positive line 410 supplies current from the dual contactor 380 to the other electrical control circuits. A start-stop motor switch 411 is connected to the positive line 410 and to the control circuit 412 for the pump motor 164. The motor switch 411 is provided with switch actuator 418 on the face of the control box 357, for operation of the switch 411. A dial light 413 is connected to the positive line 410 through the start-stop switch 411, for illuminating a portion of the face of the control box 357. A resistance 414 is connected in series with the light 413 to limit the voltage to the light 413.

A normally closed centrifugal switch 415 is connected to the positive line 410 and to a red light 416, having a resistance 417 connected in series therewith to limit the voltage to the light 416. The centrifugal switch 415 is mechanically connected to the conveyor 78, and is driven thereby when the conveyor 78 is driven. Operation of the conveyor 78 driving the centrifugal switch 415 causes the latter to open, whereby the light 416 is not illuminated. When the conveyor 78 is stopped, or if the conveyor 78 should be stopped by jamming, the centrifugal switch 415 closes and the light 416 will then be illuminated, providing a signal on the face of the control box 357 to the machine operator indicating stoppage of the conveyor 78.

A head motors start-stop switch 420 is connected to

the positive line 410 through the switch 421, the latter controlling the operation of the conveyor 78. The start-stop switch 420 is connected to a motor control circuit 422 for starting and stopping operation of the head motors 71, 72 and drive the cutter arms 60, 65. By connection of the head motors switch 420 through the conveyor switch 421, the head motors 71, 72 cannot be operated unless the conveyor 78 is operating to discharge from the mining machine 30 the material mined by the cutter arms 60, 65. Electrical connections 408 connect the pump motor circuit 412 to the head motors circuit 422, so that the head motors 71, 72 cannot be started unless the pump motor 164 is first started. When the pump motor 164 is stopped, the head motors 71, 72 are also stopped, and the operation of the other devices of the machine are also stopped as will appear in greater detail hereinafter.

An ammeter 423 is connected to the left head motor 71 across a shunt 424, and a second ammeter 425 is connected to the right head motor 72 across a shunt 426. The ammeters 423, 425 are placed at opposite sides of the face of the control box 357, corresponding to the disposition of the head motors 71, 72, and show the current being supplied to the head motors 71, 72, thereby providing a measure of the load on the head motors 71, 72, and indicating to the machine operator any overloads on either or both motors.

An ammeter 427 is connected to the pump motor 164 across a shunt 428, and is centrally disposed on the face of the control box 357 to indicate the current drawn by the pump motor 164, which is a measure of the load on the pump motor 164. A voltmeter 429 is connected across the positive line 410 and the negative line 409 to show the supply voltage to the equipment. The voltmeter 429 is placed on the face of the control box 357 adjacent the pump motor ammeter 427.

A tachometer generator 430 is connected to the gear case 73 of the head motors 71, 72 to be driven thereby, and is electrically connected to a resistance box 431, through which current is supplied to a tachometer 432 for indicating the speed of the drive of the head motors 71, 72, which is related to the speed of the cutter arms 60, 65 and serves to provide an indication of whether the cutter arms 60, 65 are operating properly. The tachometer 432 is centrally disposed on the face of the control box 357 above the pump motor ammeter 427 and the voltmeter 429.

Switches 435, 436 are each connected to the positive line 410, and are alternately operated to energize the solenoids 437, 438, respectively, of the pilot control valve 250 for the right traction motor 35. The pilot control valve 250 controls the operation of the volume control valve 278 to govern the supply volume of hydraulic fluid to the right traction motor 35, thereby controlling the speed thereof. The switches 435, 436 are alternately operated by a switch actuator 439 on the face of the control box 357.

Switches 441, 442 are each connected to the positive line 410 and are adapted to be alternately closed to energize solenoids 443, 444, respectively, of the pilot control valve 251, which controls the operation of the volume control valve 277 to govern the supply volume of hydraulic fluid to the left traction motor 34, thereby controlling the speed thereof. The switches 441, 442 are adapted to be alternately closed by a switch actuator 445 on the face of the control box 357.

A three position conveyor switch 421 is connected to the positive line 410 for alternate energization of one or the other of the solenoids 448, 449 of the pilot control valve 254, which controls the direction of operation of the conveyor 78. When the switch 421 is operated to energize the solenoid 448 the conveyor 78 is operated in the reverse direction. The conveyor 78 is operated in reverse when it becomes jammed with material, and by such reverse operation the jammed material is re-

leased and the conveyor 78 may then be restored to operation for discharging material from the end of the mining machine 30. The switch 421 is operated to energize the solenoid 449 for operating the conveyor 78 for discharge of material from the mining machine 30. The switch 421 has an intermediate "off" position in which neither solenoid 448, 449 is energized, the conveyor 78 being rendered inoperative by setting the switch 421 in this position. A switch actuator 450 is provided on the face of the control box 357 for setting the switch 421 to any one of its three positions. The start-stop switch 420 for the head motors 71, 72 is connected to the positive line 410 through the switch 421. The start-stop switch 420 is operative to start the head motors 71, 72 only when the conveyor switch 421 is in the conveyor discharge position for energization of the solenoid 449. This is a safety feature which prevents operation of the head motors 71, 72 while the conveyor 78 is either inoperative, or is operated in reverse direction, since the head motors 71, 72 must not be driven unless the conveyor 78 is operative to collect the mined material from the mine face and to discharge the same from the rear of the mining machine 30.

The conveyor-high speed tram switch 452 is connected to the positive line 410, and has two positions for energizing one or the other of solenoids 227, 228 of the pilot control valve 226, which controls the operation of the pilots 240, 241. Energization of the solenoid 227 operates the pilots 240, 241 to set the flow control valves 245, 246 for operation of the hydraulic conveyor motor 83, as previously described. Operation of the switch 452 to energize the solenoid 228 operates the pilots 240, 241 to set the flow control valves 245, 246 for operation of the hydraulic traction motors 34, 35 at high speed. The switch 452 is provided with a switch actuator 455 on the face of the control box 357, having two positions corresponding to the positions of the switch 452.

Head separate switches 457, 458 are each connected to the positive line 410 and are alternately operated. Upon closing of the switch 457 the solenoid 459 is energized, and the alternate closing of switch 458 energizes solenoid 460, the solenoids 459, 460 being included in the pilot operated control valve 168 which controls the operation of the cylinder and piston mechanisms 57 for separating the mining heads 48, 49 and for bringing them back together. A switch actuator 461 is provided on the face of the control box 357 for alternately closing one or the other of switches 457, 458. The switch actuator 461 is normally maintained in a neutral position in which neither switch 457, 458 is closed.

Head tilt switches 463, 464 are each connected to the positive line 410, and are alternately operated for energization of the solenoids 465, 466, respectively. The solenoids 465, 466 are included in the pilot operated control valve 167 which controls the operation of the hydraulic cylinder and piston mechanisms 56 for tilting the mining heads 48, 49. A switch actuator 467 is provided on the face of the control box 357 for alternately closing one or the other of the switches 463, 464. The switch actuator 467 is normally maintained in a neutral position in which neither switch 463, 464 is closed.

Head raise switches 468, 469 are connected to the positive line 410 and are alternately closed to alternately energize the solenoids 171, 172, respectively, of the pilot operated control valve 166, which controls the operation of the cylinder and piston mechanisms 55 for raising and lowering the mining heads 48, 49 and the support 45 therefor. A switch actuator 470 is provided on the face of the control box 357 for alternately closing one or the other of the switches 468, 469. The switch actuator 470 is normally maintained in a neutral position in which neither switch 468, 469 is closed.

Right crawler switch 472 is connected to the positive line 410 and is operative to energize one or the other of solenoids 473, 474 of pilot control valve 222. The

pilot control valve 222 operates the pilot 223 for the reversing valve 225 that controls the delivery of hydraulic fluid to the right traction motor 35. When the switch 472 is operated to its forward position the solenoid 473 is energized, setting the reversing valve 225 for delivery of hydraulic fluid to the right traction motor 35 for operation of the latter in a forward direction to propel the mining machine 30 forwardly. Operation of the switch 472 to its reverse position energizes the solenoid 474, which sets the reversing valve 225 for delivery of hydraulic fluid to the right traction motor 35 to operate the latter in the reverse direction, as when backing the mining machine 30 away from the mine face. The switch 472 has a neutral position in which neither solenoid 473, 474 is energized, and the reversing valve 225 is set in a neutral position in which no hydraulic fluid is delivered to the right traction motor 35 to render the latter inoperative, whereby the mining machine 30 remains stationary. The switch 472 is provided with a switch actuator 475 having forward, neutral, and reverse positions corresponding to the positions of the switch 472 for operating the latter.

The left crawler switch 477 is connected to the positive line 410 and is adapted to energize one or the other of the solenoids 205, 206 of the pilot control valve 203 for operating the pilot 220 of the reversing valve 224 for setting the latter to deliver hydraulic fluid to the left traction motor 34, to drive the latter in either a forward or reverse direction, or alternately to render the left traction motor 34 inoperative by not delivering any hydraulic fluid thereto. The operation of the left crawler switch 477 is the same in all respects as the right crawler switch 472. A switch actuator 478 for the switch 477 is provided on the face of the control box 357. Each of the switch actuators 475, 478 is formed as a crank extending in opposite directions towards each other with the positions thereof corresponding to the crawler traction treads 33, 32 controlled thereby. The switch actuators 475, 478 are so disposed that they may be operated together with one hand for simultaneous operation of the left and right traction motors 34, 35 and the corresponding crawler traction treads 32, 33.

A tachometer generator 480 is connected to the drive from the right traction motor 35 for operation thereby. The tachometer generator 480 is connected to a resistance box 481 to which there is also connected a tachometer 482. The current delivered by the tachometer generator 480 to the tachometer 482 provides an indication on the tachometer 482 of the speed of the right crawler traction tread 33. A second tachometer generator 484 is connected to the drive from the left traction motor 34 for operation thereby. The tachometer generator 484 is electrically connected to a resistance box 485 to which there is also connected a tachometer 486. The current supplied by the tachometer generator 484 to the tachometer 486 provides an indication on the tachometer 486 of the speed of the left crawler traction tread 32.

The tachometers 482, 486 are placed on the face of the control box 357 at the right and left sides thereof, respectively, corresponding to the respective crawler traction treads 33, 32. The resistance boxes 481, 485 are connected through switches 487, 488 to set the range of the tachometers 482, 486, respectively, for low speed operation of the crawler traction treads 32, 33, as when advancing the mining machine 30 into the mine face during the mining operation. The switches 487, 488 are ganged to the conveyor-high speed switch 452, and when the latter is set for high speed operation of the crawler traction treads 32, 33 the switches 487, 488 are correspondingly set to connect the resistance boxes 481, 485 for high range operation of the tachometers 482, 486, respectively. The tachometers 482, 486 show the speed of advance of the mining machine 30 and provide an indication to the operator at the remote control station as to whether the mining operation is progressing at a

satisfactory rate. The tachometers 482, 486 also indicate the speed of the crawler traction treads 32, 33 relatively to each other, that is to say whether one of the crawler traction treads 32, 33 is operating faster than the other, whereby suitable adjustment can be made to equalize the speed of the crawler traction treads 32, 33 by operation of switch actuators 439, 445. Also adjustment can be made of the speed of the crawler traction treads 32, 33 to operate them at unequal speeds, as when steering.

Referring to FIG. 13, there is illustrated the control box 357 at which the machine operator takes his station for operating the mining machine 30. The operation of the mining machine 30 is started by moving the pump motor switch actuator 408 to the start position 5 which sets the pump motor 164 in operation to drive the hydraulic pumps 160, 161, 162 for supplying hydraulic fluid to the hydraulic system of the machine. The pump motor switch actuator 408, after being moved to the start position, automatically returns to its neutral position, and may thereafter be used to stop the operation of the pump motor 164, the operation of the vari-stop operation of the head motors 71, 72, by virtue of the connections 408 between the pump motor circuit 412 and the head motor circuit 422. By stopping operation of the pump motor 164, the operation of the various hydraulic devices is also stopped since the supply of hydraulic fluid under pressure is cut off thereby.

Following the starting of the pump motor 164, the head motors start-stop switch actuator 433 is moved to start position for energizing the head motor circuit 422 for operation of the head motors 71, 72. The switch actuator 433 automatically returns to its neutral position and may thereafter be used to stop the operation of the head motors 71, 72. The head motors start-stop switch 420 is connected through the conveyor switch 421 to the positive line 410 of the control circuit. Therefore, before the head motors 71, 72 can be started, the conveyor switch actuator 450 must be in discharge position, which sets the conveyor 78 for discharging the mined material from the mining machine 30. Setting the conveyor switch actuator 450 to the discharge position connects the head motors start-stop switch 420 to the positive line 410. Movement of the conveyor switch 450 to either the neutral position, in which the conveyor 78 is rendered inoperative, or to the reverse position, in which the conveyor 78 is operated in reverse direction, also serves to disconnect the head motor start-stop switch 420 from the positive line 410 whereby the head motors 71, 72 are rendered inoperative. Thus, the mining machine 30 cannot be operated to remove material from the mine face unless the conveyor switch actuator 450 is first moved to its discharge position for operation of the conveyor 78 to remove the mined material from the mine face and to discharge the same at the rear of the mining machine 30. As another step in starting the head motors 71, 72, the switch actuator 455 is set to conveyor position prior to starting head motors 71, 72, for delivery of hydraulic fluid under pressure to the conveyor hydraulic motor 83 for operation of the latter.

After starting the pump motor 164, setting the controls for the conveyor 78, and starting the head motors 71, 72, the switch actuators 475, 478 are moved from the neutral position to the forward position, whereby the mining machine 30 is advanced into the mine face by the crawler traction treads 32, 33. During the mining operation the tachometer 432 shows the speed of operation of the head motors 71, 72, and the ammeters 423, 425 show the load on the head motors 71, 72, by which it can be determined by the operator if the mining mechanisms are functioning properly. The pump motor ammeter 427 shows the load on the pump motor 164, by which it can be determined if the pump motor is operating properly, and the voltmeter 429 shows the voltage delivered to the mining machine 30.

The tachometers 482, 486 show the speed of the right

and left crawler traction treads 33, 32, respectively, by which it can be determined if the latter are being driven at equal speeds for advancing the mining machine 30 in a straight line. Should it be found that the crawler traction treads 32, 33 are operating at unequal speeds the right and left crawler switch actuators 439, 445 can be operated individually to equalize the speed of the crawler traction treads 32, 33. Either of the switch actuators 439, 445 may be operated to increase or decrease the speed of the respective crawler traction treads 33, 32. Operation of both switch actuators 439, 445 at the same time and in the same direction, may be utilized to increase or decrease the rate of advance of the mining machine 30, as may be required by the condition of the mine face.

During the mining operation the switch actuators 418, 419 are maintained in the automatic position, which opens the switches 399, 400, thereby rendering the signaling system operative to illuminate the lights 386, 390, 394, 398 in accordance with the location of material harder than the coal as found by the sensing devices of the cutter arms 60a, 60b, 65a, 65b, each of which includes a sensing device. The lights 386, 390, 394, 398 are distributed in correspondence with the limits of the determinate mine face area 91 from which the coal is removed by the cutter arms 60, 65, so that by observation of the lights, the disposition of the relatively harder material in the mine face is readily apparent. Upon encountering the relatively harder material in the mine face, the mining heads 48, 49 are adjusted by use of the switch actuators 461, 467, 470. The switch actuator 461 is provided for separating the mining heads 48, 49 by raising the mining head 49 relatively to the mining head 48 and, likewise can be utilized to bring the mining heads 48, 49 together by lowering the mining head 49 relatively to the mining head 48. Thus the vertical disposition of the mining heads 48, 49 can be adjusted in accordance with the height of the mine seam in which the mining machine 30 is operating to remove a maximum height of coal from the mine face. The vertical adjustment of the mining heads 48, 49 is made in accordance with the signals provided by the lights 386, 390, 394, 398, which indicate the disposition of material relatively harder than the coal in the mine face. The switch actuator 461 is normally maintained in a neutral position, and after movement thereof to either the up or down position it automatically returns to the neutral position upon release thereof.

The head tilting switch actuator 467 is used to tilt the mining heads 48, 49 forward or back to follow a descending or ascending seam of coal. Operation of the switch actuator 467 is also in accordance with the signals provided by the lights 386, 390, 394, 398, which show the disposition of the material in the mine face that is relatively harder than coal. The disposition of this relatively harder material will indicate to the operator whether the coal seam is following a descending or ascending path in the mine, and the adjustments of the mining heads 48, 49 are made accordingly. The head raise switch actuator 470 is utilized to raise and lower the mining heads 48, 49 and the support 45 therefor, along with the tilting of the mining heads 48, 49 to follow the ascending or descending path of the coal seam. Each of the switch actuators 467, 470 is normally maintained in a neutral position, and following operation of either of the switch actuators 467, 470, it will return automatically to the neutral position upon release thereof. The switch actuators 461, 467, 470 for adjusting the mining heads 48, 49 control the operation of the valves 166, 167, 168, and since the latter are connected in series, as previously described, the switch actuators 461, 467, 470 are operated individually.

The operation of the mining machine 30 may be stopped by moving the pump motor actuator 408 to stop position. This stops the operation of the head motors

71, 72 as well as the pumps 160, 161, 162, thereby rendering all of the mechanisms of the mining machine 30 inoperative. Another procedure for stopping the operation of the mining machine 30, which is followed when it is desired to tram the machine away from the mine face following a mining operation, is to move the lights switch actuators 418, 419 to the on position, which renders the signal lights 386, 390, 394, 398 operative to show the positions of the cutter arms 60a, 60b, 65a, 65b in the quadrants of operation thereof lying in the perimeter of the determinate mine face area 91 from which coal is removed during the mining operation. The head motors 71, 72 are then operated by means of the head motor switch actuator 433 to bring the aforesaid cutter arms out of contact with the side walls of the mine, the movement of the cutter arms to the withdrawn positions being indicated by the signal lights 386, 390, 394, 398. When the cutter arms 60a, 60b, 65a, 65b are withdrawn from the side walls of the mine, the head motors 71, 72 are stopped by operation of the switch actuator 433, and thereafter the pump motor 164 is stopped by operation of the switch actuator 408.

Following stoppage of the mining machine 30 the switch actuator 455 is operated to the high speed position 25 for tramping at high speed. The conveyor switch actuator 450 is set to off position, although it will be understood that with the switch actuator 455 set to high speed position there will be no hydraulic fluid supplied to the conveyor hydraulic motor 83. The pump motor switch actuator 408 is then operated to start the pump motor 164, and the switch actuators 475, 478 for the crawler traction treads 32, 33 are operated to either the forward or reverse positions, depending upon the direction in which it is desired to tram the mining machine 30. 30 As previously described, during tramping at high speed the hydraulic fluid which is normally delivered to the conveyor hydraulic motor 83 for operation thereof is delivered to the traction motors 34, 35 and combined with the hydraulic fluid delivered from the traction pump 161 for operating the traction motors 34, 35 at high speed. During tramping the tachometers 482, 486 will indicate the speed of the crawler traction treads 33, 32, respectively and the switch actuators 439, 445 may be operated to increase or decrease the tramping speed, or may be operated to steer the mining machine 30 by operation of the crawler traction treads 32, 33 at different speed, as previously described. In the course of tramping the mining machine 30, or before such tramping is started the switch actuators, 461, 467, 470 may be operated, as previously described, for adjusting the position of the mining heads 48, 49 as may be found necessary.

By the instant invention there is provided a mining machine which can be operated from a station remotely located with respect to the mine face. The mining machine includes a control system connected to the various mechanisms of the mining machine for controlling said mechanisms and the mining machine as a whole from the remotely located control station. The control system includes means providing signals at the control station 55 indicating the disposition in the mine face of material which is different from the selected material of the mine face that it is desired to remove by the mining operation. The disposition of the different material is indicated at the control station with respect to the mining mechanisms 60 of the mining machine, whereby said mining mechanisms can be adjusted with respect to the mine face for operation thereof to remove only the selected material from the mine face. While the invention has been described herein as applied to a mining machine that is remotely controlled and operated, it will be apparent that various elements of the invention are adaptable to use with mining machines that are not remotely operated and controlled.

Obviously those skilled in the art may make various 75 changes in the details and arrangements of parts without

departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. In a mining machine adapted to remove material from a mine face, mining means adapted to be advanced into the mine face for removing material therefrom by a rotary cutting and breaking action, means for rotating said mining means, means for advancing said mining means into the mine face during the rotation thereof, a signaling system for indicating the rotary position of said mining means, said signaling system including signaling elements related to rotary positions of said mining means, each of said signaling elements being included in an individual circuit, a commutator having the segments thereof connected in said individual circuits, a brush rotated with the mining means and contacting the commutator to establish a connection to a signaling element through a commutator segment that is related to the rotary position of the mining means, and means to energize an individual circuit including said brush and a commutator segment to operate the signaling system to provide a signal showing the rotary position of the mining means.

2. In a mining machine adapted to remove material from a mine face, mining means adapted to be advanced into the mine face for removing material therefrom by a rotary cutting and breaking action, means for rotating said mining means comprising, a shaft on which said mining means is supported, means for advancing said mining means into the mine face during the rotation thereof, a signaling system for indicating the rotary position of said mining means, said signaling system including signaling elements related to rotary positions of said mining means, each of said signaling elements being included in an individual circuit, a commutator disposed concentrically with the shaft and having segments thereof connected in said individual circuits, a brush supported for rotation with said shaft, said brush being disposed in contact with the commutator to establish a connection to a signaling element through a commutator segment that is related to the rotary position of the mining means, and means to energize an individual circuit including said brush and a commutator segment to operate the signaling system to provide a signal showing the rotary position of the mining means.

3. In a mining machine adapted to remove selected material from a mine face, mining means adapted to be advanced into the mine face for removing selected material therefrom by a rotary cutting and breaking action, means for rotating said mining means, means for advancing said mining means into the mine face during the rotation thereof, a signaling system for indicating the advance of said mining means into material that is of different hardness than said selected material, said signaling system including elements related to rotational positions of the mining means, said mining means including means for operating said system comprising, a portion of the mining means yieldably supported on a relatively rigid portion of the mining means and adapted to move relatively to the rigid portion of the mining means when it is advanced into material of different hardness than said selected material, and means responsive to the relative movement of the yieldable portion of the mining means for operating the signaling system to provide a signal by means of said elements related to the rotational position of the mining means.

4. In a mining machine adapted to remove selected material from a mine face, mining means adapted to be advanced into the mine face for removing selected material therefrom by a rotary cutting and breaking action, means for rotating said mining means, means for advancing said mining means into the mine face during rotation

thereof, a signaling system for indicating the advance of said mining means into material that is of different hardness than said selected material, said signaling system including elements related to rotational positions of the mining means, said mining means including means for operating said system in response to the advance of said mining means into material that is of different hardness than said selected material to provide a signal by means of said elements related to the rotational position of said mining means.

5. In a mining machine adapted to remove selected material from a mine face, mining means adapted to be advanced into the mine face for removing selected material therefrom by a rotary cutting and breaking action, means for rotating said mining means, means for advancing said mining means into the mine face during rotation thereof, a signaling system for indicating the advance of said mining means into material that is of different hardness than said selected material, said signaling system including elements related to rotational positions of the mining means, said mining means including means for operating said system in response to the advance of said mining means into material that is of different hardness than said selected material to provide a signal by means of said elements related to the rotational position of said mining means.

6. In a mining machine adapted to remove selected material from a mine face, mining means adapted to be advanced into the mine face for removing selected material therefrom by a cutting and breaking action, means for advancing said mining means into the mine face, a signaling system for indicating the advance of said mining means into material that is of different hardness than said selected material, said signaling system including elements related to positions of the mining means in the mine face, said mining means including means for operating said system in response to the advance of said mining means into material that is of different hardness than said selected material to provide a signal by means of said elements related to the position of said mining means in the mine face, a control station disposed at a position spaced from the mine face and the mining machine and including said elements of the signaling system arranged in correspondence with rotary positions of the mining means.

7. In a mining machine adapted to remove selected material from a mine face, mining means adapted to be advanced into the mine face for removing selected material therefrom by a cutting and breaking action, means for advancing said mining means into the mine face, a signaling system for indicating the advance of said mining means into material that is of different hardness than said selected material, said signaling system including elements related to positions of the mining means in the mine face, said mining means including means for operating said system in response to the advance of said mining means into material that is of different hardness than said selected material to provide a signal by means of said elements related to the position of said mining means in the mine face.

8. In a mining machine adapted to remove selected material from a mine face, mining means adapted to be advanced into the mine face for removing selected material therefrom by a rotary cutting and breaking action, means for rotating said mining means, means for advancing said mining means into the mine face during rotation thereof, a signaling system for indicating the advance of said mining means into material that is of different hardness than said selected material, said signaling system including signaling elements related in position to rotational positions of the mining means, said signaling elements each being included in an individual circuit for operation of said signaling elements, said mining means including

means for operating said signaling system in response to the advance of said mining means into material that is of different hardness than said selected material comprising an operating element for activating one of said individual circuits to operate a signaling element related in position to the rotational position of the mining means thereby to provide a signal related to the rotational position of said mining means.

9. In a mining machine adapted to remove selected material from a mine face, mining means adapted to be advanced into the mine face for removing selected material therefrom by a rotary cutting and breaking action, means for rotating said mining means, means for advancing said mining means into the mine face during rotation thereof, a signaling system for indicating the advance of said mining means into material that is of different hardness than said selected material, said signaling system including signaling elements related in position to rotational positions of the mining means, said signaling elements each being included in an individual circuit for operation of said signaling elements, said mining means including means for operating said signaling system in response to the advance of said mining means into material that is of different hardness than said selected material comprising an operating element for activating one of said individual circuits to operate a signaling element related in position to the rotational position of the mining means thereby to provide a signal related to the rotational position of said mining means, a control station disposed at a position spaced from the mine face and the mining machine and including said elements of the signaling system arranged in correspondence with rotary positions of the mining means.

10. In a mining machine adapted to remove selected material from a mine face, mining means adapted to be advanced into the mine face for removing selected material therefrom by a cutting and breaking action, means for advancing said mining means into the mine face, a signaling system for indicating the advance of said mining means into material that is of different hardness than said selected material, said signaling system including signaling elements related in position to positions of the mining means in the mine face, said signaling elements each being included in an individual circuit for operation of said signaling elements, said mining means including means for operating said signaling system in response to the advance of said mining means into material that is of different hardness than said selected material comprising an operating element for activating one of said individual circuits to operate a signaling element related in position to the position of the mining means in the mine face thereby to provide a signal by means of said elements related to the position of said mining means in the mine face, a control station disposed at a position spaced from the mine face and the mining machine and including said elements of the signaling system arranged in correspondence with positions of the mining means.

11. In a mining machine adapted to remove selected material from a mine face, mining means adapted to be advanced into the mine face for removing selected material therefrom by a cutting and breaking action, means for advancing said mining means into the mine face, a signaling system for indicating the advance of said mining

means into material that is of different hardness than said selected material, said signaling system including signaling elements related in position to positions of the mining means in the mine face, said signaling elements each being included in an individual circuit for operation of said signaling elements, said mining means including means for operating said signaling system in response to the advance of said mining means into material that is of different hardness than said selected material comprising an operating element for activating one of said individual circuits to operate a signaling element related in position to the position of the mining means in the mine face thereby to provide a signal by means of said elements related to the position of said mining means in the mine face.

12. In a mining machine adapted to remove selected material from a mine face, mining means adapted to be advanced into the mine face for removing selected material therefrom by a rotary cutting and breaking action, means for rotating said mining means, means for advancing said mining means into the mine face during rotation thereof, a signaling system for indicating the advance of said mining means into material that is of different hardness than said selected material, said signaling system including signaling elements related to rotational positions of the mining means, said signaling elements being included in an individual circuit for operation of said signaling elements, a commutator having segments thereof each connected in one of said individual circuits, a brush contacting said commutator segments and rotated relatively to the commutator by the mining means, said mining means including a normally open switch connected to the brush for energizing one of said individual circuits through a commutator segment when the switch is closed, said mining means including a yieldable portion which is yieldable in response to the advance of the mining means into material that is of different hardness than said selected material, said yieldable portion of the mining means engaging said switch for closing said switch when the mining means is advanced into material that is of different hardness than said selected material to operate one of said signaling elements related in position to the rotational position of the mining means thereby to provide a signal related to the rotational position of said mining means.
